Inventor:

James A. Charnley
By Walter B. Vincent, Atty.

UNITED STATES PATENT OFFICE.

JAMES A. CHARNLEY, OF PROVIDENCE, RHODE ISLAND.

MACHINE FOR ENGRAVING WIRE.

SPECIFICATION forming part of Letters Patent No. 290,318, dated December 18, 1883.

Application filed October 10, 1881. (No model.)

To all whom it may concern:

Be it known that I, JAMES A. CHARNLEY, of Providence, in the State of Rhode Island, have invented a new and useful Machine for 5 Engraving Wire; and I do hereby declare that the following specification, taken in connection with the drawings making a part of the same, is a full, clear, and exact description thereof.

10 Figure 1 is a side elevation. Fig. 2 is a top view. Fig. 3 is an end elevation. Fig. 4 is a top plan view of my machine, with the beam d , guide d' , and brace d'' removed. Fig. 5 is a perspective view of beam d , guide d' , and brace d'' .

15 My machine is designed for the engraving of wire to be used in the ornamentation of jewelry and other articles; and it consists in the construction, combination, and operation of a 20 pair of engraving - rollers, pinions, endless screw, blocks, set-screws, and guides, as hereinafter described.

25 The engraving or impressing of any ornamental figure or pattern upon small wire which is itself to be used in the ornamentation of other articles, if done by hand, would require an amount of time and labor that would render its manufacture utterly impracticable.

30 The object of my invention is to overcome this difficulty and to manufacture ornamental wire with such rapidity, and consequently so cheap, that it will be available for the ornamentation of a great variety of articles.

35 In the drawings, a is the frame of the machine, which is secured to a suitable bed. Within the frame a are two rolls, $c c'$, which have engraved upon their exterior surfaces the figure or pattern which it is desired to place upon the wire. The journals of the rolls 40 $c c'$ extend beyond the frame a at one end, and are provided with pinions $b b$. The roll c is stationary, while the roll c' is adjustable through the sliding blocks $w z$, in which it finds a bearing, and the set-screws $f f$.

45 h is an endless screw working in the pinions $b b$, and to which motion is imparted through the band-wheel e . There are two guides, d' , one attached to the lower side of the frame a , and the other on the upper side, which extend, 50 one upward and the other downward between

the rolls $c c'$ until their thinner ends nearly meet, which hold the wire g in place between and at the bite of the rolls $c c'$. These guides are V-shaped, or made thin at one of their ends, so that they may extend up and down 55 between the rolls $c c'$. The thicker ends are provided with two slots, d^3 , running lengthwise the guide, by means of which, together with brace d^2 and screws, they are secured to beam d . Then beam d is secured to frame a 60 by means of screws. The slots d^3 in the guides d' are for the purpose of allowing the guides to be adjusted to different size wires.

g is a piece of wire passing through the rolls $c c'$. This wire is conducted to and from the 65 machine by pipes or tubes attached to the machine in a proper position. The rolls $c c'$ slightly converge toward that end from which the wire is delivered. The roll c has a fixed bearing, and the axis of this roll is at right angles to the frame a ; but the roll c' has adjustable sliding blocks $w z$, and the axis of roll c' is set farther from the axis of roll c at one 70 end than at the other end. The surfaces of the rolls are therefore closer together at one 75 end than at the other. The roll c' is adjusted by set-screws $f f$, which turn in screw-bearings in one end of frame a , and are properly secured to blocks $w z$; or I may make the rolls smaller at the unengraved ends, than at the 80 engraved ends, which would answer the same purpose as canting the roll c' .

The operation of my invention is as follows: Motion is imparted to the endless screw h by the band-wheel e , which communicates motion 85 to the rolls $c c'$ through the pinions $b b$. The wire g is now introduced between the rolls $c c'$ between the guides d' . The rolls $c c'$ both rotate in the same direction, so that while the tendency of one is to carry the wire downward 90 the tendency of the other is to carry it upward, the result of which is, that it is retained in its place while it is turned by and submitted to the action of the engraved surfaces. The rolls $c c'$, converging slightly, as described, together 95 with the action of the engraved surfaces, draw the wire through without the assistance of other feeding mechanism, as the pattern to be wrought on the wire is engraved upon the surface of the rolls on a spiral line.

The space between the rolls c c' may be regulated to the different sizes of wire by the set-screws f f .

What I claim as my invention, and desire 5 to secure by Letters Patent, is—

A machine for engraving wire, consisting of frame a , endless screw h , roll c , supported in fixed bearings, roll c' , canted and supported in adjustable bearings w z , both having on 10 their surfaces an engraved pattern passing

spirally around said rolls, beams d , braces d' , and guides d'' , having slots d'' , adapted to hold the wire in place, and capable of being adjusted to hold different size wires, all arranged substantially as described, and for the purposes 15 set forth.

JAMES A. CHARNLEY.
